(57) **CLAIM**

The ornamental design for a refrigerator, as shown and described.

DESCRIPTION

FIG. 1 is a perspective view of a built in refrigerator showing my new design;

FIG. 2 is an enlarged partial perspective view of the built in refrigerator in an alternate position;

FIG. 3 is a front elevational view of that shown in FIG. 1; and,

FIG. 4 is an enlarged partial perspective view of the built in refrigerator shown in another alternate position.

The dotted lined appearing on the refrigerator drawers represents surface ornamentation.
